UNITED STATES PATENT OFFICE.

ADOLPH FICK AND RUDOLPH FICK, OF BOONE, IOWA.

CROSSING-GATE APPARATUS.

Application filed May 7, 1924. Serial No. 711,686.

To all whom it may concern:

Be it known that we, ADOLPH FICK and RUDOLPH FICK, citizens of the United States, residing at Boone, in the county of Boone 5 and State of Iowa, have invented certain new and useful Improvements in a Crossing-Gate Apparatus, of which the following is a specification.

This invention relates to improvements in 10 grade crossing gates.

The primary object of this invention is the provision of a safety system for use at 15 grade crossings, such as the intersection of a railway with a highway, embodying an improved gate operating apparatus which will necessitate the stopping of vehicles and other traffic traveling on the highway upon approaching the grade crossing.

A further object of this invention is the 20 provision of a novel type of safety gate construction and operating mechanism embodying means by which the crossing gates will be operated by vehicles and other traffic traveling along the highway.

25 A further object of this invention is the provision of safety apparatus for use at grade crossings including normally closed gates and an operating mechanism therefor adapted to be operated by vehicles and other 30 traffic traveling along the highways, so that traffic of necessity has to come to a stop upon approaching the grade crossing, the gate operating means being controlled according to the condition of the railway traffic adjacent 35 the grade crossing.

A further object of this invention is the provision of crossing gates for use at grade crossings upon opposite sides of the railway bed which crosses a highway, and including 40 a novel electrical operating means controlled by a three way circuit maker and breaker system which includes switches adapted to be operated by vehicles traveling along the highway; the railway bed embodying 45 a novel circuit maker and breaker arrangement operable by trains passing along the railway, so that upon approach of a train the gate operating circuit may be rendered inoperative.

50 Other objects and advantages of this invention will be apparent during the course of the following detailed description.

In the accompanying drawings, forming 55 a part of this specification, and wherein similar reference characters designate corre-

sponding parts throughout the several views.

Figure 1 is a plan view of a grade crossing, showing diagrammatically the improved safety apparatus and the wiring systems 60 for control thereof.

Fig. 2 is a plan view of a platform which is positioned in the highway adjacent the grade crossing and over which vehicle traffic must of necessity pass as it approaches 65 the grade crossing.

Fig. 3 is a longitudinal cross sectional view taken through the platform construction illustrated in Figure 2, substantially on the line 3—3 of Figure 2. 70

Figs. 4 and 5 are cross sectional views taken substantially on their respective lines in Figure 3 of the drawings.

Fig. 6 is a cross sectional view taken through a supporting detail of the improved 75 platform.

Fig. 7 is a cross sectional view taken through a portion of the improved platform, showing certain circuit controlling switch means adapted to be operated by 80 movement of said platform.

Fig. 8 is a cross sectional view taken through the crossing gate housing operating details thereof.

Fig. 9 is a cross sectional view through 85 the gate housing, on the line 9—9 of Figure 8.

Fig. 10 is a cross sectional view taken on the line 10—10 of Figure 8, showing gate 90 controlling mechanism.

Fig. 11 is a fragmentary view showing novel circuit controlling details for the operating mechanism of the crossing gate.

Figs. 12 and 13 are cross sectional views taken through certain details of the circuit control arrangement illustrated in Fig. 11. 95

Figure 14 is a side elevation of the gate structure with the gate closed.

Fig. 15 is a side elevation of the gate 100 structure with the gate open or vertically arranged.

Fig. 16 is a front elevation of a warning signal which may be used in connection with the improved safety apparatus. 105

In the drawings, wherein for the purpose of illustration is shown but the preferred embodiment of this invention the letter A may generally designate the improved safety apparatus, which is used adjacent a 110

grade crossing which consists of the intersection of a highway B with a railway bed C. The safety apparatus A preferably comprises gates D and D' located in proximity to the highway B at opposite sides of the railroad bed C. Motors E and E' are respectively provided as a part of the operating mechanism for the gates D and D'. A circuit F is provided for the motors E and E', which includes a battery G, and a three way circuit maker and breaker circuit H. Circuit maker and breaker means K operable when a train passes along the railroad bed C is provided in connection with each set of rails of the railroad C.

The gate structures D and D' are altogether similar, and as illustrated in Figures 14 and 15 of the drawings the same are of the vertical swinging type, being pivotally mounted, as by a shaft 20, upon suitable standards 21 which may be encased in a housing 22 similar to the ordinary gate housing now found in use. A counterbalancing weight 23 is preferably carried by shaft 20 including a screw threaded shank 23^a located exteriorly of the housing 22, adapted to adjustably receive a ball 23^b, in order to facilitate the easy opening or closing of the gate arm D or D'.

Each of the gate arms adjacent its pivotal end is provided with an offset 24^a so that the gate arm is tangentially pivoted with respect to the shaft 20. Concentrically arranged with the shaft 20 is a series of lenses 28, 29 and 32. The housing 22 preferably supports a bracket 35^a which is adapted to detachably support a lamp 35 thereon having a lens facing in the direction of the lenses 28, 29 and 32 of the gate arm. The lenses 28, 29 and 32 are so arranged with respect to the lamp lens that when the gate is closed or horizontally arranged, the red lens 28 will have the rays of light from the lamp 35 emanating therethrough in the direction of approaching traffic. As the gate or arm swings upward the red lens 29 will come into alignment with the lens of the lamp 35, so that the rays of light will show red in the direction of approaching traffic. The green lens 32 which aligns with the lens of the lamp 35 when the gate or arm is vertically positioned or open, as is illustrated in Figure 15 of the drawings, indicates to approaching traffic that the way is clear. The arm intermediate its ends may carry a relatively large disc 43 as a means of better indicating the presence of the gate. While the preferred position of the gate lenses and lamp have been shown, other locations for the lamp may be selected, depending upon the construction of the housing desired.

In connection with operation of the gate its motor E or E', as the case may be, is suitably mounted within the housing 22

upon any bracket structure 24 which may be connected to one of a pair of standards 21^a. The drive shaft 25 of the motor preferably has a pinion 26 keyed thereto, which is in meshing relation with large gear 27 keyed to a shaft 27^a which bears in standards 21^a. A pinion 27^b also keyed on shaft 27^a meshes with a large gear 27^c keyed on the gate shaft 20. Thus, the proper gear ratio may be obtained for lifting gate D. As a means of breaking the circuit through the motor E when the gate or arm D has been elevated to clear the highway, a circuit maker and breaker construction is placed in the circuit F adjacent the motor E or E', as the case may be, which includes a pair of spaced contacts 30 and 31, carried in insulated relation by one of the standards 21 of the arm construction D, and an insulation disc 33 carried for rotation by the pivot shaft 20 of the gate arm D, and upon which disc 33 a metal conducting plate 34 is affixed, for cooperation in permitting the circuit to bridge between the spaced contacts 30 and 31. The operation of the semaphore or gate D is through approximately 90°, and hence the metal conducting plate 34 should only bridge the circuit between the contacts 30 and 31 through this 90° movement, or less than such movement. As the motor E is operating to elevate the gate or arm D the disc 33 will rotate with the pivot shaft 20 and the plate 34 will slide over the contacts 30 and 31. When the gate D is almost vertical the plate 34 rides out of engagement with the contacts 30 and 31 and thus breaks the circuit through the motor E and stops the same. To prevent the gate or arm D from immediately dropping an electromagnet 36 is provided which is placed in the circuit F by a shunt circuit 37. In the shunt circuit 37 is disposed a circuit maker and breaker construction which controls the operation of the electromagnet 36, and which circuit maker and breaker construction includes the spaced contacts 38 and 39 and a metal bridging plate 40 which is carried by an insulation disc 41; the latter being keyed to the pivot shaft 20 of the gate. The electromagnet 36 is of course not energized during operation of its motor E or E', as the case may be, but as the circuit through its motor is broken the plate 40 carried by the insulation disc 41 will be moved into engagement with the spaced contacts 38 and 39 to close the shunt circuit 37 and energize the electromagnet 36 for holding the gate details in substantially the position illustrated in Figures 10 and 15. An arm 90 may be pivotally supported upon a pin 91 within the housing, adjacent the motor E, and this arm 90 at one end thereof is provided with an armature 92 for the electromagnet 36. The arm 90 on the opposite side of the pivot

thereon is preferably provided with a detent 94 pivoted thereon, which is normally urged by a spring 95 against a pin 96 supported upon the arm 90. The detent 94 at the 5 outer end thereof may be provided with a tooth or a recess, as desired, which is adapted to mesh between the teeth of a gear 97 which may be keyed upon the motor shaft 25. Upon energization of the electro- 10 magnet 36, which will only happen when the signal arm is raised, the detent 94 will be moved to engage the motor gear 97 to hold the motor gear fixed, and as is apparent the gate will be held in its vertical position so 15 long as the electromagnet is active. It is apparent that so long as the electromagnet is active, the detent will swing to engage the pin 96 incident to tendency of the weight of the gate to reverse the motor shaft. When 20 the electromagnet 36 is cut out of the circuit 37 the weight of the gate will swing the gear 97 so that the arm 90 will be moved out of obstructing relation with the gear 97, and the gate may fall to a closed position. 25 A stop 98 may be provided for limiting the amplitude of movement of the arm 90 away from the electromagnet 36.

In the open position of the gate the weight of the gate is just slightly overbalanced at one side of the pivot shaft 21, so 30 that when the magnet 36 is deenergized the gate will fall by gravity to a closed position. It is of course understood that the discs 33 and 41 and the contacts respectively associated therewith provide a circuit control arrangement and these discs are always disposed in a definite relation so that when the motor circuit is cut off the shunt circuit of the electromagnet will be closed, or vice 35 versa.

Referring to certain novel features of the highway B, the same at the approach to the railroad bed or right of way C is narrowed, as at 45, and a short distance from the gates 45 D and D' platform constructions M and M' are respectively placed, and over which vehicles or other traffic must pass prior to entering the grade crossing. Preferably a short distance from the platform structures, 50 and of course remote from the grade crossing, warning signs 47 may be placed, preferably upon a foundation 48 in the middle of the highway, serving as an indication to traffic that they are about to cross a railroad line. This warning sign 47 may have 55 any suitable warning or instructing indicia thereon, substantially as is illustrated in Figure 16 of the drawings.

The platform structures M and M' are 60 of course similar, and but one will be described. It consists of a cementitious foundation 50, which includes the side walls 51, and a bottom 52; the top edges 54 of the side walls 51 being disposed flush with the top 65 surface of the highway or roadway B, to

provide a compartment 55 within which details of the platform are located. Foundation piers 56 are provided in the compartment 55, upon the bottom 52 of the foundation structure 50 which supports thereon the 70 substantially E-shaped guide members 58 provided as a means of limiting the upward and downward movement of the platform. The platform proper consists of the longitudinally extending side beams 60, which 75 may be of the conventional I-shaped structure, and which are tied together by cross strips 61, and support thereon the transverse planks 62 to provide the platform; the top surfaces of the planks 62, when the platform proper is normally positioned, being disposed flush with the top surface of the highway B. The I beams 60 are resiliently supported upon the piers 56, as by strong 80 spiral supporting springs 64; the piers 56 85 having upwardly extending conduit projections 65 receiving thereover the spring 64 to properly position the same upon the pier, and the I beams 60 detachably carrying the depending cylindrical shaped members 65^a in 90 95 detachable screw threaded engagement adapted to be disposed within the spring 64 to properly position the spring with respect to the I beam and with respect to the projection upon the pier 56, substantially after the manner illustrated in Figure 6 of the drawings. The facing edges of the projections 65 and 65^a are, of course, spaced for a considerable distance; this distance defining the movement which the platform 100 has when a vehicle rides thereover to depress the same. The laterally extending flange 67 of each I beam 60 plays an important part in limiting the upward and downward amplitude of movement of the platform proper; this flange 67 being adapted 105 to play in the space between the upper and intermediate flanges 69 and 70 of the bracket or guide members 58, substantially as is illustrated in the drawings. The springs 64 are, of course, normally under compression and urge the I-beams upward until the flanges 67 thereof engage the top flanges 69 of the guide members 58, so that the top surface of the platform proper is positioned flush with 110 the top surface of the highway B. On a pier 70 positioned in the compartment 55 a switch 71 is positioned, which is a three way switch adapted for operation in the three way circuit H as will be subsequently described; this switch 71 including an operating plunger or plungers 72 adapted to be moved by engagement therewith of a projection 73 when the platform is depressed.

Referring to the three way wiring circuit H, the same includes the lines 75 and 76 which extend across the railroad line C and at each end provide the spaced contacts 77 and 78 as part of each of the switch structures 71. Each switch structure 71, of 115 120 125 130

course, includes the movable switch arm 79 for cooperation with its respective contacts 77 and 78, as a means of closing the circuit or opening the same in either of the lines 75 and 76 of the circuit H, in accordance with well known principles of three way circuit wiring systems.

The railroad bed C may of course include any number of tracks. In connection with 10 each set of rails in the road bed C, a circuit is provided, which includes a battery or other energizer 80, and in which circuit is disposed a relay 81. The rails in which the battery 80 and its respective relay 81 is disposed may 15 be insulated, as at 82 from the rails which align therewith, at a suitable distance from the grade crossing, so that the circuit in the track rails will be confined to a reasonable distance on each side of the grade crossing. 20 Relay 81 is preferably placed at one end of the circuit forming track section while the battery 80 is placed at the other end, so that when a truck 84 of a car passes over the rails of the track it will short circuit the 25 battery 80 and cause the spring operated armature 84^a of the relay 81 to move away from the electromagnet part of the relay. This relay armature 84^a forms a part of the gate operating circuit F, and when the relay 30 is short circuited the arm 84^a moves to break the circuit F, and renders the same inoperative.

Referring to the operation of the improved safety apparatus, the road B has 35 been narrowed at 45 on each side of the grade crossing, to make the same adaptable for one way traffic only. Assuming a vehicle is approaching the platform M, the occupants thereof will be warned by means 40 of the sign 47 of the grade crossing which they are approaching. The vehicle will of course approach the grade crossing at low speed, and as the normal position of the gates or arms D and D' is the closed position, the vehicle will come to stop immediately over the platform M. It is to be 45 noted in connection with the positioning of the platform M that the highway in which it is positioned is narrowed at the point of 50 the positioning of the platform so that some portion of the vehicle must pass thereover to depress the same below the normal position of the same, and to thus operate the three way switch 71. If the tracks of 55 the railroad C are clear, depression of the platform M will close the three way switch and throw the arm 79 thereof for closing of the circuit F in the motors E and E', operating the same, so that the gates D and D' 60 will be elevated. When the gates D and D' have been elevated to the desired degree the motor circuits are cut off as above mentioned, and the electro-magnets 36 are energized for holding the gates D and D' open, 65 so that the vehicle may pass across the rail-

road C. As the vehicle rides over the platform M' the three way switch 71 thereof will be operated to break the circuit F, de-energizing the magnets 36 and permitting the gates D and D' to fall into a closed position. Should a train or other railroad unit be passing over a track of the railroad C the relay 81 for the particular circuit of that track will be deenergized by the short circuiting of the same, so that the armature 84^a of that relay 81 will move to open the circuit F, and notwithstanding the fact that a vehicle traveling along the road B has passed upon the platform M, the gates D and D' will not be elevated until the tracks are clear. The safety system obviously contemplates a one way traffic passage. The improved safety gate or apparatus is primarily adapted for use in country districts, and where it becomes necessary for a line of vehicles to pass the grade crossing the gates D and D' may be held in elevated position manually until the vehicles have passed. While in Figure 16 the indicia supporting post has been shown as embedded in concrete, such construction is not necessary, as rocks can be piled about the same to prevent vehicles from running into the same. Another feature of construction which may be provided, is that of placing white fencing or rocks along the margins of the road where the same widens around the warning sign 47.

From the foregoing description of this invention it is apparent that a safety gate apparatus and system for grade crossings has been provided which is automatic in operation and which will effect a positive safeguard for traffic traveling over the highway, in no sense being dependent upon the whim of the individual highway traveler.

Various changes in the shape, size, and arrangement of parts may be made to the form of invention herein shown and described, without departing from the spirit or the scope of this invention.

We claim:

1. In a safety system for railway and highway grade crossings the combination of a gate, a circuit, a motor for said circuit, means connecting the motor to the gate for operation of the same, and circuit maker and breaker means for said circuit operated by trains running over the railway bed to maintain said motor circuit inoperative when a train is running over or approaching said grade crossing.

2. Safety apparatus for highway and railway grade crossings comprising gates on the highway at opposite sides of the railway, motors for operating said gates, a circuit for said motors including three way circuit maker and breaker switches located in the highway for operation by approach,

ing vehicles, and circuit maker and breaker means for rendering the motor circuits inoperative when railroad traffic is approaching the grade crossing.

- 5 3. In a safety system for grade crossings, the combination of a gate, a motor for operating the gate, a circuit for said motor including a battery, circuit maker and breaker switches located in the highway for controlling said circuit, said circuit maker and breaker switches adapted to be operated by vehicles traveling over the highway, and circuit makers and breakers in said first mentioned circuit operable by trains on the railroad approaching said grade crossings to render the first mentioned circuit inoperative.

- 20 4. Grade crossing safety apparatus comprising gate means normally closed across the highway in advance of the grade crossing, motor means for operating said gate means, a circuit for said motor means, a movable platform located in the highway over which a vehicle traveling along the highway must pass, switch means operably associated with the platform for controlling the motor circuit, and circuit maker and breaker means for the motor circuit operable to open the motor circuit upon the passing of a train over the railroad portion of said grade crossing.

- 25 5. In a safety construction for railroad and highway crossings the combination of gates for the highway at each side of the railroad, motors for operating said gates, said gates being of such nature as to close when their motors are inoperative, a three way circuit for the motors of said gates including three way switches located in the highway at opposite sides of the railroad and in advance of the gates of the highway, platforms in the highway over which the ve-

hicle traffic must pass to operate said three way switches for controlling said motors, a relay, circuit means placing the relay in connection with the rails of the railroad track, a battery for the relay circuit so located with respect to the relay that when a train passes over the tracks the relay current will be short circuited, said relay including an armature normally acting as a circuit maker and breaker for the gate motor circuits and adapted to render the gate motor circuit inoperative when the relay is short circuited.

55 6. In a safety system for railway and highway grade crossings the combination of a gate for controlling vehicular traffic across the grade crossing, an electric circuit, a gate operating motor for said circuit, means operated by vehicular traffic on the highway for closing said circuit to operate the motor, and circuit maker and breaker means associated with the railway of the grade crossing operable by trains running over the railway to also control said circuits.

65 7. In a safety system for railway and highway grade crossings the combination of a gate normally adapted to assume a closed position across the highway to prevent travel of vehicular traffic across the grade crossing, an electric circuit, a motor for said circuit, means connecting the motor with said gate for operating the latter, means adapted to be operated by travel of vehicular traffic over the highway to close said circuit for operating the motor and elevating the gate, and circuit maker and breaker means for said circuit of the motor operable by trains running over the railway bed in the vicinity of the grade crossing to maintain said motor circuit inoperative.

75 ADOLPH FICK.
RUDOLPH FICK.
